(57) **CLAIM**

The ornamental design for a food container, substantially as shown and described.

DESCRIPTION

FIG. 1 is a top front perspective view of a food container, shown in a closed position;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof;

FIG. 7 is a front elevational view thereof;

FIG. 8 is a front elevational view thereof with a tab open; and,

FIG. 9 is a top plan view thereof, shown in a fully open position.

The dot-dash broken lines are shown to represent boundaries and form no part of the claimed design. The evenly spaced broken lines are shown to represent parts of the article which form part of the claimed design.

1 Claim, 6 Drawing Sheets
